TYPEWRITING MACHINE

Henry L. Pitman, Hartford, Conn., assignor to
 Underwood Elliott Fisher Company, New York,
 N. Y., a corporation of Delaware

Application May 10, 1938, Serial No. 207,062

5 Claims. (Cl. 197—176)

This invention relates to typing-machine carriages, and deals with devices for cushioning the mechanism-wear and noise engendering impact of the carriage with a tabulating stop or any other carriage-jump-arresting stop, and definitely controlling the tendency of the carriage to rebound at said impact.

An object of the invention is to provide improved impact-cushioning and rebound-controlling devices that are reliable in operation and are constructed of simple parts that may be applied economically to typing machines.

There is employed a tabulating-stop rack structure that is removably attached to the carriage by an easily interlockable and separable connection so that a setting of tabulating stops carried by the rack may be removed, along with the rack, from the machine for replacement by another rack carrying a different setting of stops.

A further object of the invention is to dispose a cushioning and rebound-controlling device between the stop-carrying rack and the carriage, and to adapt such device so as to freely permit removal and replacement of the rack.

25 A feature of the invention is in adapting the aforementioned easily interlockable and separable connection between the carriage and rack so as to permit movement of the carriage in tabulating direction upon arrest of the rack by a counter-stop and to check this movement by a resilient cushion such as a spring, whereby to cushion the impact.

At the impact of the rack with a counter-stop, the spring may yield inasmuch as it absorbs the impact shock by permitting the carriage to move independently in tabulating direction relatively to the arrested rack. The spring then recovers, thereby moving the carriage back relatively to the arrested rack.

40 A further feature of the invention resides in definitely braking the backward or recovery movement of the carriage relatively to the rack so as to minimize the momentum of said backward movement and thereby counteract recoil of both the carriage and rack from the counter-stop. The braking may be effected definitely by means of a friction connection, and a further feature of the invention is in means adapted for regulating the braking effect.

45 The definite braking or friction connection may be arranged so as to be effective also during the impact-absorbing movement of the carriage relatively to the rack in tabulating direction, said friction connection thereby cooperat-

ing with the cushioning spring to cushion the impact.

In a typewriting machine such as the Underwood, the carriage runs upon front and rear rails mounted on the machine frame. The front rail 5 may be of channel section presenting upper and lower flanges. It is a further feature of the present improvements to provide, instead of the usual rollers spaced at intervals on and along the front cross-bar of the carriage-frame to bear on said flanges, a continuous rail or bar on said front carriage-frame bar adapted to fit slidably against said front rail flanges. Said bar may be co-extensive substantially with the length of the carriage-frame and may be attached to said front carriage-frame cross-bar so as to reinforce the latter while, at the same time, serving, as a part presented by the carriage, to engage said rail flanges. The continuous bar, slidably engaging the front rail, also serves to keep the carriage steady in its travel and thereby conduces 10 to evenness of the typing.

Other features and advantages will hereinafter appear.

In the accompanying drawings:

Figure 1 is a rear view section on the trace 1—1, Figures 4 and 7, showing details of the carriage-impact-cushioning and rebound-controlling devices.

Figure 2 is a plan-view diagram of the carriage, carriage-feeding mechanism and the machine frame.

Figure 3 is a perspective of portions of the carriage tabulating mechanism and said impact-cushioning and rebound-controlling devices.

Figure 4 is a top plan view showing the left side portion of the tabulating rack as attached to the carriage, and the cushioning and rebound-controlling devices.

Figure 5 is a perspective showing the tabulating rack detached from the rack-mounting part of the carriage and showing said part mounting the impact-cushioning and rebound-controlling device.

Figure 6 is a cross-section view at the middle 45 of the interlocked tabulating rack and said rack-mounting part.

Figure 7 is a top plan view, showing the right side portion of the tabulating rack and its attachment to the carriage.

A typing carriage C, Figures 2 and 3, comprises a frame 15 adapted to travel on front and rear rails 16, 17 mounted on a typewriter frame 18.

At operation of type keys 14 to drive types 20 55

to a platen 21 mounted in said carriage C, the usual escapement mechanism, represented by escapement wheel 22, Figure 2, is actuated for resulting letter-feed of the carriage by a spring 5 motor 24 connected to the carriage by a draw-band 25. The escapement mechanism includes the usual type-key-controlled dog-device (not shown), normally restraining the escapement wheel 22 and carriage C, the carriage mounting 10 a letter-feed rack 26 engaging a pinion 27 coupled to the escapement wheel 22.

A carriage tabulating mechanism may include 15 a series of denominational counter-stops 29 in the form of reeds, Figure 3, assembled in a housing 30 on the frame 18, said reeds being adapted to be elevated selectively, by means of denominational tabulating key-levers 31 to bring their upper ends into the path of column stops 32 settable in a rack structure 33 removably attached to the carriage, as will presently be described. At elevation of any one of the denominational counter-stops 29, an arm 34 thereof dis- 20 places a universal bar 35 fixed to a rock-shaft 36 journaled in the housing 30 to rock said shaft counter-clockwise of Figure 3. Said rock-shaft 25 36, when thus rocked, acts through the usual connection represented diagrammatically by the dot-and-dash line 39, Figure 2, to lift the letter-feed rack 26 from the escapement pinion 27, thereby releasing the carriage for a resulting 30 tabulating jump to the left, the jump being arrested when the column stop 32 on the carriage is 35 intercepted by the elevated counter-stop 29. At release of the operated denominational tabulating-key lever 31, the elevated counter-stop 29 is retracted by its individual spring 40, Figure 2, and concomitantly, the universal bar 35 and its rock-shaft 36 are caused to be restored so that the 40 letter-feed rack reengages the escapement pinion 45 27 in the usual manner to settle the carriage at the tabulated-to position. The tabulating key and counter-stop mechanism and associated carriage-releasing means are not described in further detail herein since such detail is exemplified in Patent No. 1,858,447 to W. F. Helmond, dated May 17, 1932.

The open carriage frame includes side members 41 and front and rear cross-bars 42, 43, joining said side members. The rear cross-bar 43 has 50 fixed thereto, by screws 44, side brackets 45, each presenting an upright wall 46. A bracket-spanning angle bar 47 has one leg 48 fixed vertically to the bracket walls 46 by screws 49, Figures 3 and 5. A horizontal leg 50 of said angle bar 47 55 has at its left end a notch or slot 51 adapted to receive slidably by way of the open left end of the slot, Figure 5, a reduced neck formed on a rack-structure stud 52 by a groove 53. The groove 53 is slightly wider than the thickness of 60 the slotted part of the angle bar so that an upper stud-flange 54, formed by said groove may rest slidably on the upper face of the horizontal angle-bar leg 50. The rack-structure stud 52 is entered first into the angle-bar slot 51 after which the 65 rack-structure 33 is swung clockwise of Figures 4, 5 and 7 from a cocked stud-introducing position to enter another rack-structure stud 56, grooved similarly to the stud 52, into a notch or slot 57 at the right end of angle bar 47, said slot 70 57 opening at the rear edge of said angle bar. The rack-structure 33 includes a front rack 58 surmounted by the studs 52, 56. Fixed to the ends of said rack 58 and extending rearwardly therefrom are arms 60 presenting upturned ears 75 61 which mount a rear rack 59 having letter

spaced notches 62, Figure 6, on its under side similar to letter spaced notches 63 of the front rack 58.

With the rack-structure studs 52, 56 entered 5 into their respective notches 51 and 57, as in Figures 4 and 5, a latch hook 64 may engage the front of a stud 65, Figure 7, projecting upwardly from the angle-bar 47 to releasably keep the rack-structure 33 in place. The right-hand notch or slot 57 has a left edge which normally abuts the 10 reduced neck of the right stud 56 as at 67, Figure 7, to stop leftward displacement of the rack-structure on the carriage. The latch hook 64 is formed on a plate 68 pivoted to the rack-structure, as at 69, Figures 3 and 7. A spring 71 yieldably holds the latch-hook plate 68 in rack-structure-latching position. A finger piece 72 on said latch-hook plate serves for swinging the plate counter-clockwise of Figure 7 to withdraw the latch hook 64 from the stud 65 preparatory to 15 withdrawing the right-rack-structure stud 56 rearwardly from its companion angle-bar slot 57; the rack structure being then completely detachable from the carriage by moving it leftward out of the left slot 51.

Each column stop 32 may be formed on a unit 20 74 having front and rear teeth 75 and 76 for articulation with the notches 63, 62 of the front and rear racks 58, 59; and each unit 74 further has ears 77 adapted to hook over the top of the 25 rear rack 59. Each unit 74 is withdrawable end-wise from the racks 58, 59 and is placeable at any one of the letter-spaced rack stations afforded by the rack notches. A stop-placing scale 78 is fixed to the rack structure, as at 79, Figures 3 and 6. Each unit 74 has a detent spring 80 30 adapted to clip into a groove 81 of the front rack 58 to keep the unit in place.

Fingers 82 project rearwardly to underlie the 35 rack-structure arms 60 to support the latter, as at 83, Figure 3, to keep the rack-structure 33 from sagging about its loose connections to the angle bar 47 at the studs 52, 56. Said fingers 82 have upturned forward ends 84 rigidly fixed to the carriage by the screws 49 that secure the 40 angle bar 47 to the carriage bracket walls 46.

A double-angle bar 85 has a horizontal leg 86, Figures 1 and 6, immovably fixed to the top of the angle bar 47 as by spot-welding or riveting; and a forwardly projecting leg or flange of said 50 double angle bar forms a cross rail 87 engageable with a stationary guide (not shown) to cooperate to support the weight of the parts that are carried by the brackets 45.

The rack structure 33 and the easily inter-lockable and separable connection for removably attaching it to the carriage are, as so far described, substantially along the lines disclosed in my co-pending application Serial No. 72,348, filed April 2, 1936.

The devices for cushioning the impacts of the 55 column stops 32 with the counter-stops 29 at the arrests of tabulating jumps of the carriage and for controlling rebound of the carriage, will now be described.

Upon the carriage proper and, therefore, overlying the horizontal leg 86 of the double-angle bar 85 is a bar 90 having longitudinal slots 91, 92, Figures 1 and 4. A stud 93, riveted into the horizontal legs 50, 86 of the angle-bars 47, 85, 70 as at 94, Figure 1, projects through the slot 91 of said bar 90. Another stud 95, riveted into said horizontal angle-bar legs, as at 96, is received in the slot 92 of said bar 90 and has a head 97 between which and the horizontal leg 86 the bar 75

90 is slidably retained. Said stud 95 has an upward extension 98 between which and a stud 99, riveted into the bar 90, as at 100, a spring 101 is stretched. Said spring 101 thus holds said bar 5 90 with one end of either or both of its slots 91, 92 in abutment with the respective studs 93, 95, as in Figure 1. The bar 90 has an end 103 adapted so that when the rack structure 33 is in place it abuts the side of said stud flange 54, as at 104, 10 Figure 1.

It will be perceived now, referring to the rear elevation, Figure 1, in which the carriage-tabulating movement is to the right, that at the interception of a column stop 32 on the rack structure 15 33 by the counterstop 29, the rack structure, including the stud 52, is arrested; and, since the stud flange 54 abuts the end of the slide bar 90 on the carriage, said slide bar is also arrested. But the slots 91, 92 in said bar 90 leave the carriage proper, together with its angle bars 47, 85, 20 free to move independently by momentum relatively to said thus arrested bar 90 and rack structure 33. To permit such independent movement of the carriage, the slots 51, 57 of the angle bar 25 47 are elongated to the right of their respective studs 52, 56 as in Figures 4 and 7. It will be perceived that the rack structure retaining latch-hook 64 is also adapted to permit such independent carriage-movement. The spring 101 30 yields with said independent movement of the carriage proper relatively to the arrested bar 90. The spring 101 is strong enough to yield or stretch only limitedly whereby to resiliently overcome and check said movement and thereby absorb and cushion the impact of the carriage-arrest.

After checking said independent movement of the carriage, the stretched spring 101 resiliently recovers and thereby effects a reverse movement of the carriage and its angle bars 47, 85 relatively to the arrested rack-structure 33 and slide 40 bar 90.

The following devices brake, and therefore retard said reverse movement so that its momentum is minimized by the time the studs 93, 95 45 again abut the ends of their respective slots 91, 92, as in Figure 1, and, therefore, tendency of the carriage, together with the rack-structure, to rebound or recoil from the counterstop 29, is minimized.

50 The stud 93 projects through a slot 106, Figure 1, in a plate 107 which loosely overlies and is movable with the slide bar 90 relatively to the angle bars 47, 85 in that the spring stud 99 of said slide bar 90 closely fits a hole in said plate 107. The stud 93 has an upwardly extending screw 108 passing through a leaf-spring 109 55 adapted to press upon the plate 107 when said spring 109 is held under strain by means of a washer 110 and a nut 111 threaded upon said screw 108.

60 The plate 107, thus pressed by the spring 109, in turn presses upon the slide bar 90 so that the latter presses upon the leg 86 of the underlying angle bar 85. The leaf spring 109 thus imposes a frictional braking effect, at the contacting surfaces of said slide bar 90 and the angle-bar leg 86 and also at the contacting parts of the plate 107 and the spring 109, which retards relative movement of said bar 90, and the carriage with its angle bars 47, 85. The frictional braking effect thus minimizes the momentum of the reverse carriage movement that occurs when the spring 101 recovers resiliently after its impact-absorbing stretch, and, therefore, liability of rebound or recoil of the carriage from the counter-

stop 29 is minimized and proper reengagement of the letter feed rack 26 and pinion 27 is insured. The frictional braking effect may be immediately effective at the start of said reverse carriage movement. The braking pressure of the leaf 5 spring 109 may be regulated by adjusting the nut 111 up or down upon the screw 108 and the adjustment may be held by means of a check nut 112. The frictional braking effect also obtains when the carriage moves independently in tabulating direction following arrest of the rack structure 33, and is thus cooperative with the spring 109 in cushioning the impact so that said spring does not have to yield excessively. It will be understood, of course, that the spring 101 is made 15 strong enough to overbalance the frictional braking effect of the spring 109.

Referring now to improved means whereby the carriage is guided in its travel by the front rail 16: Said front rail 16 is of channeled cross-section, Figure 3, presenting upper and lower flanges 114. To the front cross-bar carriage frame 15, and substantially coextensive therewith, Figure 2, is attached a bar 115 of a height to fit slidably and substantially without up-and-down play between said upper and lower rail flanges 114. Said bar 115 may be attached, as by screws 116, to bosses 117 provided in suitable number upon and extending forwardly from the vertical leg of said carriage-frame cross-bar 42, the latter being, in 30 the present machine, of angular cross-section. It is found that such bar 115 slides very freely and therefore with negligible friction between said upper and lower rail flanges 114 and requires very little lubrication. The carriage frame 15 35 may have the usual Underwood collars or lugs 118 adapted to embrace the round rear rail 17 and to slide along the latter. Such rear-rail contact of the carriage holds the latter against fore and aft play so that the front face of the front 40 bar 115 need not contact the front rail 16.

Said bar 115 is an inexpensive medium of contact of the carriage with the front rail as compared with the usual ball-bearing-mounted or large diameter rollers heretofore employed. 45 Moreover, said bar 115 reinforces the carriage-frame bar 42 structurally so that liability of strain or breakage of the carriage frame is avoided, such breakage or strain otherwise being liable to occur as when it is attempted to lift the machine by taking hold of the carriage when the latter projects laterally beyond the front rail 16, as in Figure 2. The front bar 115 always affords a large spread of contact with the front rail 16 to keep the carriage from teetering in its letter-feeding 55 movements, thereby conducting to evenness of the typing. The upper and lower surfaces of the bar 115 may be provided with notches 119 adapted to prevent accumulation of dust or dirt between the sliding surfaces.

The column-stop including units 74 for which the rack structure 33 is devised, may have tappets (not particularly shown herein) adapted to actuate denominational elements of computing mechanism that may be combined with the typewriter mechanism as set forth in my aforesaid application No. 72,348. In order to support the rack 58 against flexure, said rack may have on its front face a groove 120 adapted to fit slidably a rack-supporting stud 121, Figure 6, secured to the 70 vertical leg of the angle bar 47 as by a screw 122. The top of the rack may have studs 123 adapted to bear on the under side of the horizontal leg 50 of said angle bar 47 and thereby cooperate to support the rack 58 against flexure. 75

What is claimed as new is:

1. The combination with a power-urged typing carriage, or the like, releasable to jump to a counter-stop, of a rack on the carriage mounting a stop cooperative with said counter-stop, said rack having studs and the carriage having slots to receive said studs whereby the carriage may move in jumping direction relatively to the rack at the impact of the rack-carried stop with said counter-stop, a bar movably mounted on the carriage and engaging one of the rack studs so that said carriage is movable relatively to said bar at said impact, an impact-cushioning spring connecting said bar and carriage and yielding as the carriage moves relatively to said rack at said impact, and means connecting said bar frictionally to said carriage to resist frictionally and thereby retard the reverse movement of said carriage occurring as the cushioning spring recovers and moves the carriage reversely relatively to said rack and bar. 20
2. The combination with a power-urged typing carriage, or the like, releasable to jump to a counterstop, of a rack on the carriage mounting a stop cooperative with said counter-stop, said rack having studs and the carriage having slots to receive said studs whereby the carriage may move in jumping direction relatively to the rack at the impact of the rack-carried stop with said counter-stop, a bar movably mounted on the carriage and engaging one of the rack-studs so that said carriage is movably relatively to said bar at said impact, an impact-cushioning spring connecting said bar and carriage and yielding as the carriage moves relatively to said rack at said impact, and a spring pressing said bar on said carriage to cause frictional retardation of the reverse shift of said carriage occurring as the cushioning spring recovers and moves the carriage reversely relatively to said rack and bar. 35
3. The combination with a tabulating carriage, of a stop-rack, supporting means on the carriage for receiving the rack at its end portions detachably to permit ready removal and replacement of the rack at will by manipulation, said supporting means constructed to permit longitudinal movement of the carriage relatively to the rack at impact of a stop on said rack with a counterstop, and a cushioning device permanently mounted on the carriage and operatively connected to said rack to react to said longitudinal movement of the carriage to cushion said impact, 5 said cushioning device and its operative connection to said rack being arranged to permit freely said ready removal and replacement of the rack. 10
4. The combination with a tabulating carriage, of a stop-rack, a part permanently mounted on and movable longitudinally of the carriage, means for connecting said rack at its end portions to said carriage detachably so as to permit ready removal and replacement of the rack at will by manipulation, said connection means constructed to permit longitudinal movement of the carriage relatively to the rack at impact of a stop on said rack with a counter-stop, and a spring cooperative with said part to react to said longitudinal movement of the carriage to cushion said impact, 15 said impact, said rack, by being in place on the carriage, having operative connection to said part so that said carriage also moves longitudinally relatively to said part, against the urge of said spring, at said impact. 20
5. The combination with a tabulating carriage, of a stop-rack, a part permanently mounted on and movable longitudinally of the carriage, means for connecting said rack at its end portions to said carriage detachably so as to permit ready removal and replacement of the rack at will by manipulation, said connection means constructed to permit longitudinal movement of the carriage relatively to the rack at impact of a stop on said rack with a counter-stop, a spring cooperative 25 with said part to react to said longitudinal movement of the carriage to cushion said impact, said rack, by being in place on the carriage, having operative connection to said part so that said carriage also moves longitudinally relatively to 30 said part, against the urge of said spring, at said impact, and a frictional connection between said part and carriage acting to retard the spring-urged rebound or recovery movement of said carriage relatively to said rack and part. 35

HENRY L. PITMAN.
